UNITED STATES PATENT OFFICE.

JOHN P. COSGROVE AND WILLIAM J. O'NEILL, OF ORANGE, NEW JERSEY.

CHANGEABLE SIGN.

1,411,416.

Specification of Letters Patent.

Patented Apr. 4, 1922.

Application filed August 8, 1921. Serial No. 490,514.

To all whom it may concern:

Be it known that we, JOHN P. COSGROVE and WILLIAM J. O'NEILL, citizens of the United States, residing in the city of Orange, county of Essex, and State of New Jersey, have invented certain new and useful Improvements in Changeable Signs, set forth in the following specification.

In modern merchandising, it has become a common practice to display advertising matter upon placards or signs placed in the store windows or upon the interior walls, such matter usually comprising terse phrases descriptive of the goods advertised, together with the price per unit of the same. In some lines of merchandise, certain descriptive terms have come to be adopted to indicate quality, kind or grade; for example, in the meat trade, under the generic term "beef," we have "sirloin of," "prime ribs of," "short ribs of," "porterhouse," "filet of," etc. The practice is so extensive as to be nearly general, to have the signs painted upon sheets of paper to be hung in the store window, and discarded and others substituted as and when the price of the article changes or it is desired to "run" some other article, or a different grade or brand of the same article. The making of new signs becomes very expensive and adds much to the overhead expense of the business, while the delay in procuring them is often more inconvenient than their expense would seem to warrant.

In order to overcome these delays and inconveniences, as well as to effect a great saving in the ultimate cost of such signs, we have designed a system of signs wherein the generic term or name of the article to be advertised permanently printed, painted or otherwise affixed to the sign, while change strips bearing the descriptive terms are provided for attachment to the sign; price numerals are also provided so that each sign when made up is self-contained and carries full information concerning the advertised article. The specific means for attaching the change strips to the sign, so that they will not jar loose or become detached forms one of the features of our invention, since drafts of air are likely to sway the signs, or they may be carelessly struck or moved about by people passing in their vicinity.

In the accompanying drawing illustrating our invention,

Fig. 1 is a front view of a sign made up to advertise a particular kind of veal.

Fig. 2 shows a series of change strips having other descriptive terms thereon, but all applicable to veal. Also a series of numerals to indicate price per unit.

Fig. 3 is a rear view of the sign.

Fig. 4 is a vertical section.

Figs. 5, 6 and 7 are sections of different forms of fastening devices for securing the change strips to the sign.

Fig. 8 is a front view of the form shown in Fig. 7.

Figs. 9 and 10 are fragmentary rear views showing different forms of strip fastening slots.

Fig. 11 is a front view of a sign showing provision for two lines of change strips, as may be required for some classes of merchandise.

Fig. 12 shows a series of change strips particularly applicable to the sign of Fig. 11.

Similar reference numerals refer to like parts throughout the specification and drawings.

The body of the sign consists of a sheet of metal, celluloid or other suitable material as 1, having its margins turned over a stiffening wire 2 which is bent to conform to the shape of the sheet, and provided with a loop 3 extending through the margin, and by which the sign may be suspended. Upon the face of the sign the name of the particular article to be advertised is printed or painted in prominent letters as at 4, while such characters as "¢ lb.," "¢ doz." etc., or any other denominational character to represent price per unit of quantity are permanently painted or printed upon the sheet, as indicated at 5, 6. If desired, any other appropriate descriptive matter may be permanently printed upon the sheet as at 7.

Since nearly every article of merchandise is made up in various grades or qualities, many of which are on sale at the same or at different times, the specific matter upon the sign to properly describe the article offered must be so arranged and periodically changed to meet the conditions of trade. Prices of the article may also change from time to time, and it is necessary to provide the sign with means for indicating such change.

In order that such changes may be made in the descriptive matter, we have provided

strips 8 of the material of which the sign is made, and have printed thereon the various descriptive terms customarily applied to the article offered for sale, and also a duplicate series of numeral strips 9, to be fastened upon the sheet at their appropriate places, as shown, so that when the sign is made up, complete information respecting the article offered is given thereon.

10 The methods of fastening the strips 8, 9 may be various. For example: 3-sided slits 10 may be cut or punched in the body of the sheet 1, and the tang 11 formed thereby is bent backwardly so as to leave a narrow slot opening downwardly from front to back with a slight depression in the face of the sheet, which serves as a guide for the hook shaped tang 12 upon the strip 8 or 9. The tang 11 bears upon the tang 12, when in place and so firmly holds the strip.

15 In Figs. 6 and 10, we have shown the sheet 1 as provided with a horizontal slit 13 and the end slits 14, forming two tangs 15, 16, which are slightly bent as shown to form an open slot 17, into which the tang 18 is inserted. In this case, the tang 15 bears with yielding pressure upon the tang 18, and firmly holds it in place.

20 In Figs. 7 and 8, we have shown the strip fastening means as comprising a headed rivet 19 secured to the sheet 1, and the apertured tang 20 upon the strip 21, hooked over said rivet.

25 It is understood that the long strips 8 are to be provided with at least two supporting tangs, while the numeral strips, being nearly square, require not more than one tang each for their stable support.

30 If desired, provision may be made for two or more descriptive strips 8 for any particular article, as shown in Figs. 11 and 12.

35 While we have shown our sign as containing matter relating to meat and eggs, it will be understood that this is illustrative only, since it may be used for any article of merchandise. It is particularly adapted for use in meat, vegetable, grocery and hardware stores, and may be advantageously used to describe the various dishes and foods in restaurants. Its use has been found to materially reduce the usual cost of display signs which are designed to be used only once or

twice and then discarded. While we have shown no artistic ornamentation upon the body of the sign, yet it will be readily seen that it is susceptible of such ornament as the skill of the maker may suggest.

55 We claim:

1. In a sign, the combination of a sheet of metal having a reinforced margin, generic terms applicable to a particular article of merchandise printed thereon, strips of sheet metal each having printed thereon a specific descriptive term applicable to said merchandise, and means for separably attaching said strips to said sheet comprising a hook-shaped tang upon each of the strips and a receiving slot therefor in said sheet, said slot having a resilient upper wall to bear with yielding pressure upon the face of said tang to hold the same in place.

60 2. In a sign, the combination of a sheet of metal, generic terms applicable to a particular article of merchandise printed upon said sheet of metal, a strip of sheet metal having printed thereon specific terms applicable to said merchandise, and means for separably attaching said strips upon the face of said sheet comprising a hook-shaped tang upon said strip and a receiving slit therefor in 65 said sheet said slit being formed with a resilient wall depressed out of the plane of said sheet to bear with yielding pressure upon the face of said tang thereby to retain the same in place.

65 3. Means for attaching change strips to sheet metal signs comprising a hook-shaped tang upon and projecting from the edge of each of the strips, and a receiving slot therefor in said sign, one wall of said slot being resilient to bear with yielding pressure upon the face of said tang.

70 4. Means for attaching change strips to sheet metal signs comprising a hook-shaped tang upon and projecting from the edge of said strip, and a receiving slot therefor in said sign, said slot being formed by cutting a 3-sided slit in said sign and bending the tang formed thereby out of the plane of said sign to form a guide and yielding bearing for directing said strip tang to and retaining the same in place.

75 JOHN P. COSGROVE.
WILLIAM J. O'NEILL.
